UNITED STATES PATENT OFFICE

2,337,912

HALOGENATION OF NITRO COMPOUNDS

Earl T. McBee and Elizabeth F. Riley, West Lafayette, Ind., assignors to Purdue Research Foundation, La Fayette, Ind., a corporation of Indiana

No Drawing. Application August 3, 1940,
Serial No. 351,142

17 Claims. (Cl. 204—163)

Our invention relates to the chlorination of nitro compounds, and more specifically to the chlorination of organic compounds having a saturated group of at least 2 carbon atoms with a free nitro group attached thereto.

The chlorination of free nitro compounds, as opposed to salts of nitro compounds, is disclosed in our co-pending application, Serial No. 351,141. In accordance with the disclosure of this application, nitro compounds having a saturated group of at least 2 carbon atoms with a free nitro group attached thereto, are subjected to substitutive chlorination, to obtain chloronitro compounds in which the chlorine and nitro group are attached to different carbon atoms.

In this manner all of the various monochlorinated derivatives having the chlorine and nitro groups attached to different carbon atoms, may be prepared, and polychlorinated derivatives may also be produced, if desired. The preferred procedure constitutes liquid phase chlorination, utilizing substantially anhydrous reactants.

We have now found that the yields and conversions obtainable in the liquid phase chlorination process may be considerably improved if, in addition to employing substantially anhydrous reactants, the reaction mixture is subjected to the action of a dehydrating agent during the chlorination reaction. Since no water is formed in the substitutive chlorination reaction, it is difficult to explain the improved results obtainable by the use of a dehydrating agent. It is possible that small amounts of water are formed in some side reaction, with a resulting adverse effect on the chlorination reaction, but it is to be understood that our invention is not to be construed as limited to any particular theory of its operation.

The present process is applicable to the chlorination of any organic compound having a saturated group of at least 2 carbon atoms, such as an aliphatic or alicyclic group, with a free nitro group attached thereto. Our process is particularly suited for the chlorination of nitro hydrocarbons, and especially nitroalkanes of at least 2 carbon atoms. Chlorine is preferably employed as the chlorinating agent, but other chlorinating agents which are suitable for the chlorination of aliphatic hydrocarbons, and which are not adversely affected by the presence of nitro groups, may also be used if desired.

The chlorination may be carried out in accordance with known practices for the liquid phase chlorination of aliphatic hydrocarbons, and our invention is especially suited for use in liquid

phase photochemical chlorinations. The procedures for the various liquid phase chlorinations may follow in all respects the methods described in U. S. Serial No. 351,141, referred to above.

5 Reaction times and temperatures, and the amount and kind of light employed, may be chosen in accordance with prior practices, and our invention is not limited to any particular procedure in this respect. Any of the various 10 modifications of procedure, previously used in this art, may be followed, and our present invention differs from the prior art only in the use of a dehydrating agent.

Our chlorination process is particularly applicable to chlorination of various nitro hydrocarbons, and especially the nitroalkanes containing 2 or more carbon atoms. As examples of the 15 nitro compounds which may be treated in accordance with our invention, there may be mentioned 20 nitroethane, 1-nitropropane, 2-nitropropane, 1-nitrobutane, 2-nitrobutane, 1-nitro-2-methylpropane, nitrocyclohexanes, phenylnitroethane, and the like.

Any dehydrating agent which is chemically inert to the reactants, and which has dehydrating 25 action under the conditions of the reaction, may be employed. As examples of such agents, there may be mentioned phosphorus pentoxide, anhydrous calcium sulfate, anhydrous magnesium sulfate, and dehydrated silica gel. We prefer to 30 employ phosphorus pentoxide in most cases.

The dehydrating agent may be maintained in the reaction mixture in the reaction zone during the entire reaction. Alternatively, the reaction 35 mixture may be circulated successively through the reaction zone, then in contact with an insoluble dehydrating agent, and then recycled back to the reaction zone. Various other modifications or equivalent procedures will be apparent 40 to those skilled in the art.

The amount of dehydrating agent to be employed will depend upon the particular agent chosen, and the procedure utilized. If the dehydrating agent is extremely inert, chemically, or 45 is not maintained in the reaction mixture throughout the reaction, a large excess over that required will usually have no adverse effects. However, in the case of more reactive dehydrating agents such as phosphorus pentoxide, it is 50 usually desirable to employ the minimum amount which is effective in producing the maximum increase in yield and conversion. We prefer to employ phosphorus pentoxide in amounts ranging from 0.01% to 1.0% by weight, based on the 55 weight of the nitro compound being chlorinated.

Equivalent amounts of other dehydrating agents may suitably be employed.

Our invention may be further illustrated by the following specific examples:

EXAMPLE I

Substantially anhydrous chlorine was bubbled through a column of substantially anhydrous nitroethane approximately 15 inches deep in a 1.5 inch diameter glass tube, for a period of 31.5 hours. The reaction mixture was subjected to light from four 200 watt tungsten filament incandescent lights spaced approximately 2 inches from the tube walls. The heat supplied by these lights maintained the reaction mixture at a temperature of approximately 50° C. At the conclusion of the reaction, the mixture was distilled to recover unreacted nitroethane, and 1-chloro-2-nitroethane.

The same procedure was repeated with the exception that phosphorus pentoxide was incorporated in the nitroethane, in a concentration of 0.4% by weight, and that in the presence of this phosphorus pentoxide, the temperature of the reaction mixture was approximately 59° C. instead of 50° C. The following yields and conversions were obtained:

Table

Phosphorus pentoxide, percent based on weight of initial nitroethane	Conversion, percent of theoretical	Yield, percent of theoretical
0.0	2.9	7.2
0.4	17.6	42.9

EXAMPLE II

The procedure of Example I was followed for the chlorination of 1-nitropropane. One run was made in the absence of dehydrating agent, and another using approximately 0.05% of phosphorus pentoxide, based on the weight of the 1-nitropropane. The following yields and conversions were obtained:

Table

Phosphorus pentoxide, percent based on weight of initial 1-nitropropane	1-chloro-3-nitropropane		2-chloro-1-nitropropane	
	Conversion, percent of theoretical	Yield, percent of theoretical	Conversion, percent of theoretical	Yield, percent of theoretical
0.0	27.7	22.7	20.6	28.2
0.05	35.6	31.3	24.4	34.1

The examples which follow demonstrate the results obtained when utilizing substantially anhydrous reactants, but in the absence of a dehydrating agent of the type referred to above.

EXAMPLE III

Substantially anhydrous chlorine was bubbled through substantially anhydrous 1-nitropropane for 28 hours at approximately 58° C., during which time the reaction mixture was exposed in a 1.5 inch diameter glass tube three feet long, to light from 200 watt incandescent tungsten filament lights spaced approximately 2 inches from the tube wall at intervals of approximately 15 inches throughout the length of the tube. At the conclusion of the chlorination, it was found that chlorine had reacted to the extent at 24.6 parts by weight of 100 parts by weight of nitro-

propane. The reaction mixture was fractionally distilled to recover unreacted 1-nitropropane, and chlorinated products. No 1-nitro-1-chloropropane was found, but 1-nitro-2-chloropropane was obtained in a yield of 38.2% of the theoretical yield (26.6% conversion) based on 1-nitropropane. 1-nitro-3-chloropropane was obtained in a yield of 39.7% of the theoretical yield (27.7% conversion) based on 1-nitropropane.

EXAMPLE IV

Substantially anhydrous chlorine was bubbled through substantially anhydrous 1-nitrobutane for 24.5 hours at 58-60° C., while exposing the reaction mixture to light under conditions of Example III. During this period chlorine reacted to the extent of 28 parts by weight per 100 parts by weight of nitrobutane. At the conclusion of the chlorination the reaction mixture was fractionally distilled to recover unreacted 1-nitrobutane and chlorinated products. It was found that approximately 87% of the 1-nitrobutane had reacted in the process, and that no 1-chloro-1-nitrobutane was produced. Three monochlorinated 1-nitrobutanes, boiling at 67° C., 87° C., and 101° C., respectively, at 6.5 millimeters pressure, were obtained in yields of 11.8%, 27.3%, and 16.4% respectively, based on 1-nitrobutane.

EXAMPLE V

1-nitropropane was vaporized and passed, together with gaseous chlorine, in a ratio of approximately 40 parts by weight of chlorine per 100 parts by weight of 1-nitropropane, through a reaction chamber maintained at 300° C. The rate of flow was such that an average contact time of approximately 30 seconds was obtained. The reaction was effected in the absence of light. The material leaving the reaction chamber was condensed, and the condensate subjected to fractional distillation to recover unreacted 1-nitropropane and chlorinated products. Both 1-nitro-2-chloropropane and 1-nitro-3-chloropropane were obtained, but no 1-nitro-1-chloropropane was found to be present in the reaction product.

EXAMPLE VI

Substantially anhydrous chlorine was bubbled through substantially anhydrous nitroethane for 8 hours at 60° C., followed by 8 hours at 80° C. During the chlorination the reaction mixture was exposed in a 500 ml. round bottom glass flask to light from two 200 watt tungsten filament incandescent lights placed approximately two inches from the wall of the flask. The amount of chlorine reacted during this period was found to be approximately 8 parts by weight per 100 parts by weight of nitroethane. The reaction mixture was then subjected to fractional distillation to recover unreacted nitroethane, and 1-nitro-2-chloroethane. The yield of the latter product was 26.4% of the theoretical yield based on nitroethane.

EXAMPLE VII

A reaction mixture comprising 1-nitropropane and liquid chlorine, together with carbon tetrachloride as a solvent, was pumped, at a pressure of 1000 pounds per square inch, through a reaction chamber maintained at 235° C., at a rate giving a contact time of approximately 1.3 minutes. The reaction mixture contained approximately 12 parts by weight of chlorine, and 350

parts by weight of carbon tetrachloride per 100 parts by weight of 1-nitropropane. The reaction was effected in the absence of light. The pressure was released on the reaction mixture issuing from the reaction chamber, allowing unreacted chlorine to escape, and the liquid reaction product was subjected to fractional distillation to recover unreacted 1-nitropropane and chlorinated products. No. 1-nitro-1-chloropropane or 1-nitro-2-chloropropane were found, but 1-nitro-3-chloropropane was obtained in an amount constituting 6.1% conversion based on 1-nitropropane, and 40.8% based on chlorine.

It is to be understood of course, that the above examples are merely illustrative, and do not limit the scope of our invention. As has previously been pointed out our invention is broadly applicable to the liquid phase photochemical chlorination of nitro compounds having a saturated group of at least two carbon atoms, with a free nitro group attached thereto, and is not limited to any particular nitro compounds, chlorinating agents, or chlorination procedure. In general it may be said that the use of any equivalents, or modifications of procedure, which occur to those skilled in the art, is included in the scope of our invention.

This is a continuation-in-part of our copending application U. S. Serial No. 351,141, filed August 3, 1940.

Our invention now having been described, what we claim is:

1. In a process for the production of organic chloronitro compounds, the step which consists substantially in contacting chlorine with an organic compound containing a saturated aliphatic group of at least 2 carbon atoms and having a free nitro group attached to one of said carbon atoms, under substantially anhydrous conditions, in the substantial absence of other compounds tending to react with said nitro compound and with chlorine, and for a time sufficient to replace at least one of the hydrogen atoms of said hydrocarbon group with a chlorine atom, whereby a chloronitro compound is obtained containing chlorine attached to a carbon atom other than the one to which the nitro group is attached, the reaction being effected in the presence of an initially added dehydrating agent that is inert with respect to the reactants.

2. The process of claim 1 wherein said nitro organic compound is contacted with said chlorine while in the liquid stage.

3. The process of claim 1 wherein said nitro organic compound is a nitroalkane.

4. The process of claim 1 wherein said nitro organic compound is contacted with said chlorine under the action of light.

5. The process of claim 1 wherein said dehydrating agent is phosphorus pentoxide.

6. The process of claim 1 wherein said dehydrating agent is phosphorus pentoxide in amount ranging from about 0.1 to 1.0 per cent based on the weight of the nitro organic compound.

7. The process of claim 1 wherein said nitro organic compound is a nitroalkane and said dehydrating agent is phosphorus pentoxide.

8. In a process for the production of 1-chloro-2-nitroethane, the step which consists substantially of contacting substantially anhydrous chlorine with substantially anhydrous nitroethane in the liquid phase in the presence of light and phosphorus pentoxide but in the substantial

absence of other compounds tending to react with said nitroethane and with chlorine, and for a time sufficient to replace at least one of the hydrogen atoms of said nitroethane with chlorine, thereby forming said 1-chloro-2-nitroethane.

9. In the process for the production of chloronitropalanes having chlorine attached to a carbon atom other than the one to which the nitro group is attached, the step which consists substantially in contacting substantially anhydrous chlorine with substantially anhydrous nitropropane in the liquid phase in the presence of light and phosphorus pentoxide but in the substantial absence of other compounds tending to react with said nitropropane and with chlorine, and for a time sufficient to replace at least one of the hydrogen atoms of said nitropropane with chlorine, thereby forming a chloronitropropane in which the chlorine atom is attached to a carbon atom other than that to which the nitro group is attached.

10. In the process for the production of organic chloronitro compounds, the step which consists substantially in contacting chlorine with an organic compound containing a saturated aliphatic group of at least 2 carbon atoms and having a free nitro group attached to one of said carbon atoms, under substantially anhydrous conditions, in the substantial absence of other compounds tending to react with said nitro compound and with chlorine, and for a time sufficient to replace at least one of the hydrogen atoms of said aliphatic group with a chlorine atom, whereby a chloronitro compound is obtained containing chlorine attached to an aliphatic carbon atom other than the one to which the nitro group is attached.

11. The process of claim 10 wherein said organic nitro compound is contacted with said chlorine under the action of light.

12. The process of claim 10 wherein said organic nitro compound is a liquid nitroalkane.

13. The process of claim 10 wherein said organic nitro compound is a nitroalkane in the vapor phase.

14. The process of claim 10 wherein said organic nitro compound is a nitroalkane in the vapor phase and maintained under super-atmospheric pressure.

15. In a process for the production of 1-chloro-2-nitroethane, the step which consists substantially in contacting substantially anhydrous chlorine with substantially anhydrous nitroethane in the presence of light, in the substantial absence of other compounds tending to react with said nitro compound and with chlorine and for a time sufficient to replace at least one of the hydrogen atoms of said nitroethane with a chlorine atom, whereby a chloronitroethane is obtained containing chlorine attached to a carbon atom other than the one to which the nitro group is attached.

16. In a process for the production of chloronitropalanes, the step which consists substantially in contacting, in the liquid phase and in the presence of light, substantially anhydrous chlorine with substantially anhydrous nitropropane in the substantial absence of other compounds tending to react with said nitropropane and with chlorine, and for a time sufficient to replace at least one of the hydrogen atoms of said nitropropane with a chlorine atom, whereby a chloronitropropane is obtained containing chlorine attached to a carbon atom other than the one to which the nitro group is attached.

17. In a process for the production of chloronitrobutane, the step which consists substantially in contacting, in the liquid phase and in the presence of light, substantially anhydrous chlorine with a substantially anhydrous nitrobutane in the substantial absence of other compounds tending to react with said nitrobutane and with chlorine, and for a time sufficient to

replace at least one of the hydrogen atoms of said nitrobutane with a chlorine atom, whereby a chloronitrobutane is produced containing chlorine attached to a carbon atom other than the one to which the nitro group is attached.

EARL T. McBEE.

ELIZABETH F. RILEY.
